UNITED STATES PATENT OFFICE

2,554,724

ELECTRIC SWITCH

John H. Williams, Barrington, Ill., assignor to
 Oak Mfg. Co., Chicago, Ill., a corporation of
 Illinois

Application November 10, 1948, Serial No. 59,210

4 Claims. (Cl. 200—11)

1

This invention relates to an electrical apparatus and particularly to a rotary type switch. The invention in particular pertains to a rotary type switch susceptible to manufacture in small sizes and being sufficiently flexible to provide many switching combinations. A switch embodying the present invention is particularly useful for operating upon a large number of circuits simultaneously, such as for example, when switching from one wave band to another wave band in a radio receiver or transmitter or for establishing different connections in vacuum tube testers when changing from one type of tube to another type of tube. Other uses for the switch will occur to those skilled in the art.

For a more complete description of the invention reference will now be made to the drawing wherein Figure 1 is a plan view of one section of a switch construction embodying the present invention. Figure 2 is a section on line 2—2 of Figure 1. Figure 3 is a section on line 3—3 of Figure 1 and Figure 4 is a plan view along line 4—4 of Figure 2.

Referring now to the drawing, each switch section comprises rotor 10 and stator 11. Any desired number of switch sections may be ganged together upon a common shaft as desired. Suitable index mechanism may be used with such switches.

Rotor 10 comprises central insulating ring 15 of suitable insulating material such as Bakelite or the like. Ring 15 preferably has a series of slots 16 disposed at a suitable portion thereof and regularly spaced around the entire extent of the ring. Disposed against one side face of ring member 15 may be one or more metal contacts 18, these being flat and arcuate.

The angular extent of one or more of contact members 18 may be as little or as great as desired, extending from a maximum of 360° to a minimum of zero where no contact member is provided. Any number of contact members may be provided, each one having a desired angular extent with sufficient space between ends thereof to provide desired switching action. Contact member or members 18 all have inner edge 20 lying on the circumference of one circle whose center is coincident with the center of member 15. The outer edge of contact members 18 may be irregular for a purpose to be apparent later. In order to maintain contact members 18 in rotatively locked relation to member 15, contact members 18 have provided at spaced intervals fingers 21 proportioned to enter into slots 16. Preferably fingers 21 fit snugly in the corresponding slots.

2

Disposed against the outer face of contact members 18 is insulating ring 23 of suitable insulating material. Insulating ring 23 is sufficiently wide so that it extends along the face of contact 18 on both sides of fingers 21. Insulating ring 23 may conveniently have about the same dimensions as ring 15 except for the thickness. As will be apparent from the drawing, contact members 18 extend well beyond insulating members 15 and 23 so as to provide readily accessible contact portions. Cooperating with such contact portions are fixed contacts 30 of suitable material and preferably having jaws extending on opposite sides of the contact member. Fixed contacts 30 are disposed on insulating stator member 31 of Bakelite or the like. For convenience, stator member 31 may have a series of apertures therethrough at uniformly spaced intervals and any number of fixed contacts may be carried by eyelets 32 in the apertures. Stator 31 preferably, though not necessarily, has a number of fingers 34 extending inwardly and adapted to contact the outer edge of insulating ring 15. Otherwise stator member 31 has the inner portion cut to provide clearance within which the jaws of the fixed contacts may extend for proper cooperation with contact members 18.

Another set of flat contact members 33 generally similar to contact members 18 may be provided and disposed against the other side of ring 15. Contact members 33 are generally similar to contact members 18 and have fingers 35 at desired intervals for engaging one or more slots in insulating ring 15. It is understood that the fingers from contact members 33 are clear of the fingers from contact members 18 and that the slots in insulating member 15 used by one contact finger are not used by the contact finger of another contact member. In all cases, the fingers merely extend into the slots of insulating member 15 and do not extend beyond insulating member 15.

Any desired combination of contacts for contact members 33 may be provided. Cooperating with contact members 33 are fixed contacts 36. These fixed contacts may be generally similar to fixed contacts 30. Thus by shaping the outer edges of contact members 18 and 33 and by proper control of the size of the fixed contacts 30 and 36, any desired switching combinations may be obtained.

Insulating ring 37, similar to ring 23, is provided and bears against the outer face of contact members 33.

In order to maintain the assembly intact, eyelet 40 is provided. This eyelet extends within the

rotor and has the metal bent over on opposite sides of insulating members 23 and 37. In order to rotatively couple a shaft to the rotor, eyelet 40 may have a noncircular shape as shown, the shape shown being adapted to accommodate a shaft with two diametrically opposed flat portions.

What is claimed is:

1. A switch comprising a central annular insulating member having flat sides and a series of apertures therethrough, additional annular insulating members disposed against the sides of said central member, flat contact members disposed between said central member and additional members and having portions projecting beyond said insulating members for switching action and having tongues projecting into the apertures of said central member to rotatively lock said contact members, there being one tongue for an aperture with the tongues being shorter than the thickness of said central member, means for maintaining said central and additional insulating members tightly in predetermined relation to provide a rotor and fixed

contacts cooperating with said projecting contact members.

2. The structure according to claim 1 wherein a metal eyelet is provided as the means for maintaining the rotor portions intact.

3. The structure according to claim 1 wherein said fixed contacts have jaws extending on both sides of a contact member.

4. The structure according to claim 1 wherein said rotor retaining means comprises a metal eyelet and wherein a fixed insulating ring is provided for carrying the fixed contacts.
